UNITED STATES PATENT OFFICE.

CHARLES W. STIFF, OF FOXBOROUGH, MASSACHUSETTS.

TIMING ATTACHMENT FOR PHOTOGRAPHIC CAMERAS.

SPECIFICATION forming part of Letters Patent No. 336,356, dated February 16, 1886.

Application filed February 7, 1885. Serial No. 155,189. (No model.)

To all whom it may concern:

Be it known that I, CHARLES W. STIFF, of 5 Foxborough, in the county of Norfolk and State of Massachusetts, have invented certain new and useful Improvements in Timing Attachments for Photographic Cameras, of which the following, taken in connection with the accompanying drawings, is a specification.

My invention relates to an attachment for 10 photographic cameras for regulating the time of exposure to be given to the plate, and is an improvement upon the apparatus shown and described in the Letters Patent No. 299,289, granted to Nathaniel C. Bousley and myself, 15 May 27, 1884; and it consists in certain novel features of construction, arrangement, and combination of devices for automatically closing the mouth of the lens-tube at any desired predetermined time after the opening of the 20 same without the intervention of clock-work, all of which will be readily understood by reference to the description of the drawings, and to the claims to be hereinafter given.

Figure 1 of the drawings is a rear elevation 25 of my improved attachment with the shutter closed and the cap of the camera secured thereto but removed from the camera-tube. Fig. 2 is a side elevation of the same applied to the camera-tube. Fig. 3 is a front elevation of 30 the same with the rubber bulb and a portion of the pipe broken away. Fig. 4 is a similar front elevation with the tube opened by dropping the lower shutter. Fig. 5 is a central vertical section of the air-chamber, its valve, 35 and a portion of the air-supply pipe. Fig. 6 is a transverse section through the valve, and showing the locking-catch in elevation. Fig. 7 is an elevation of the valve-spindle removed from its socket and drawn to an enlarged scale. 40 Fig. 8 is another elevation of the valve viewed from a direction at right angles to Fig. 7. Fig. 9 is a transverse section of the valve on line $x-x$ on Figs. 7 and 8, and Fig. 10 is a partial transverse section on line $y-y$ on Fig. 3.

45 In the drawings, A is a plate, which may be of metal, wood, or hard rubber; but I prefer the latter, and has cut through its center the circular opening A', around which said plate is re-enforced by the rearwardly-projecting 50 circular rim A'', to which the cap B of the camera-tube B' is secured by screws, as shown in Fig. 1.

C and C' are two shutter-plates, of thin and preferably light material, which are fitted to move up and down in bearings formed by the 55 guide-strips A³ A³, secured to the front face of the plate A, as shown in Figs. 3, 4, and 10.

D is a lever pivoted to the front face of the right-hand guide-strip A³, and, extending across the front of the plate A above the opening A', projects beyond the outer edge of the left-hand guide A³, and is held in a horizontal position by the wire staple a, when not moved from said position by the application of force thereto, as will be hereinafter described. The 60 lever D is provided, near the center of its length, with the pendent arm D', terminating in a sort of V-shaped double hook, b, with which the pins c, c', and c'', set in the shutters C and C', engage at the proper times, for the 65 purpose of maintaining said shutters in their 70 uppermost or raised positions.

To the back side of the plate A, at or near its lower left-hand corner when viewed from the front, as in Figs. 3 and 4, is secured a hemispherical cup, E, provided with a downwardly-projecting hub, d, through which is formed the passage d', which communicates at its lower end with the interior of the sleeve d², formed in one piece with and extending transversely 80 across the lower end of the hub d, as shown in Figs. 1 and 5. The top of the cup E is closed air-tight by the rubber diaphragm E', secured thereon by the wire or cord e, as shown in Fig. 5.

85 F is a tapered plug-valve fitted to the sleeve d² so as to revolve therein, but extending some distance beyond said sleeve in one direction, and having formed therin the central passage extending longitudinally therefor the greater 90 part of its length, and connecting at its inner end, with the transverse passage g, arranged to coincide with the passage d' in the hub d when the valve F is in the desired position, so as to allow free communication with the interior of the cup E. The tubular end of the valve F has secured thereon the rubber tube G, the opposite end of which communicates with the interior of the rubber bulb H, as shown in Figs. 1 and 2.

95 To the side of the hub and stand portion of the cup E is secured the segmental plate I, the front edge of which is curved concentric to the axis of the valve F, and has formed upon 100

its side near said front edge a graduated scale, I', also concentric to the axis of said valve, all as shown in Fig. 2.

The valve F is secured in place by the nut 5 h, the inner portion of which is made cylindrical, and has fitted loosely thereon, so as to be freely moved about the axis of said valve without moving the valve or disturbing the nut, the lever J, provided with the index-pointer i and the outwardly-projecting stop-pin j, as shown in Figs. 2, 3, and 4.

The lever J extends beyond the front edge of the plate I, and has secured thereto the ear k, through which is made a threaded hole to receive the adjusting-screw K, and serve as a nut therefor, said screw K being mounted in the pivoted bearing l, secured to the plate I, as shown in Figs. 3 and 4, so that by turning said screw the lever J may be adjusted at will 20 to the desired point on the scale, according to the time that it is desired to expose the plate.

L is a lever firmly secured to the outer end of the valve F in position to engage with the stop-pin j, set in the lever J to limit the movement of the valve F around its axis in one direction.

The tubular end of the valve F has coiled around it, between the sleeve d' and the rubber tube G, the spiral spring m, one end of which 30 is made fast to said valve and the other end extends tangentially therefrom, and bears against the pin n, which projects from the side of the cup E in such a manner that the tension of the said spring tends to turn said valve about 35 its axis in the direction indicated by the arrow on Fig. 2. The valve F also has secured thereto the bent or scroll-like arm n', the outer end of which is arranged to engage with the hook M, pivoted to a stand secured to the rear of 40 the plate A, and pressed downward by the spring o, all as shown in Fig. 6.

A circular plate or disk, p, rests upon the diaphragm E', and is secured to the lower end of the rod N, which has its bearings in the stands 45 N', N², and N³, and has its upper end bent at right angles or so as to engage with the lower edge of the lever D, for the purpose of lifting said lever when the rod D is moved upward by the expansion of the diaphragm E', when air is 50 forced into the cup E by compressing the bulb H. The rod N and disk p are forced downward by the reaction of the spring p' whenever the pressure in the cup E is reduced by the exhaustion of the air or a portion of it 55 therefrom, the downward movement of said rod and disk being limited by the collar q coming in contact with the stand N², as shown in Figs. 1 and 2.

A bent wire, O, is connected at its lower 60 end to the movable end of the hook-lever M, and its upper end is fitted to a bearing in the stand N', the elbow or bend o' being directly above and in near proximity to the disk p, so that when the disk rises it shall carry upward 65 with it the wire O, and thus disengage the hook M from the arm n, when the reaction of the spring m will cause a partial revolution

of the valve F about its axis, sufficient to shut off communication between the cup E and the bulb H and open communication between the 70 interior of the cup E and the open air through the exhaust-passages in the periphery of the valve F. The valve F has a portion of one side cut away to form a flat surface, f', which commences sufficiently near the smaller end 75 of said valve to cover the outlet of the passage d into the interior of the sleeve d', and extends toward the other end of said valve to a point just outside of the scroll-arm n', as shown in Figs. 7, 8, and 9.

A V-shaped tapering groove, f'', is formed in the periphery of the valve F, and extending circumferentially of said valve about one-third (more or less) around the same, the center of said groove being in a plane transversely 85 of said valve cutting through the center of the passage g, and its wide end communicating with the space formed in the sleeve d' by cutting away the side of the valve to form the flat surface f', and the sides of said groove 90 converging from said wide end till they meet and the groove terminates, as shown in Figs. 7, 8, and 9.

The operation of my invention is as follows: Preparatory to obtaining the proper focus of the 95 sitter, the upper shutter, C, is moved upward until the pin c set therein engages with the upper side of one arm of the double hook b, the lever D moving slightly about its pivot to permit said pin to pass the point of said hook, 100 and falling again as soon as the pin has passed said hook, thereby carrying the point of said hook beneath said pin, so as to retain said shutter in its elevated position. When the focus has been properly adjusted, the lower 105 shutter, C', is raised, so as to cover the opening A' and carry the pin c' above the hook b, so as to rest thereon and maintain said shutter in said elevated position, as shown in Fig. 3. The operator having previously adjusted the 110 stop-pin j by moving the lever J about its pivotal bearing by means of the screw K until the index-pointer i indicates the desired 115 length of exposure upon the scale I', moves the lever L into the position indicated in Fig. 2, thereby rotating the valve F about its axis until the hook M engages with the end of the 120 arm n', when the passage g coincides with the passage d', and free communication is opened between the bulb H, and the interior of the diaphragm-covered cup E. When everything is ready for the exposure of the plate, the operator presses the bulb H in his hand to collapse it and force the air contained therein into the cup E, the result of which is to increase 125 the pressure in said cup, and thereby cause the diaphragm E' to be expanded, the rod N, disk p, and the movable end of the lever D to be raised, whereby the hook b is removed from beneath the pin c', and the shutter C' is permitted to drop and uncover the opening A', and at the same time the shutter C drops a short distance, or until it is arrested 130 by the pin c' coming in contact with the hook

b, all as shown in Fig. 4. The upward movement of the disk *p* also moves the bent wire *O* upward by coming in contact with the elbow *o'*, thereby disengaging the hook *M* from the arm *n'*, and permitting the valve to be turned about its axis by the recoil of the spring *m* until the movable end of the lever *L* comes in contact with the stop-pin *j*, thus cutting off communication between the interior of the cup *E* and the bulb *H*, and opening an exhaust-passage from the interior of said cup to the open air, of greater or less capacity, according as the lever *L* has to move through a greater or smaller arc of a circle before being arrested by the stop-pin *j*, as shown in Fig. 4. As the air in the cup *E* gradually escapes to the open air, the diaphragm *E'* contracts and tends to assume its normal position, as shown in Figs. 1, 2, and 3, and, as a matter of course, the disk *p*, rod *N*, and lever *D* gradually descend as said diaphragm contracts until the hook *b* is removed from beneath the pin *c'*, and the shutter *C* falls and closes the opening *A'*, when the exposure is completed. Of course it will be obvious to any one that the length of the exposure will in each case depend upon the length of time required for the air to escape from the cup *E*, and that will depend upon what part of the tapered *V* groove formed in the periphery of the valve *F* is brought beneath the opening of passage *d'* into the sleeve *d''*, and that is readily determined by adjusting the stop-pin *j*, so that the lever *L* and valve *F* will move a greater or less distance about their axis of motion before being arrested.

What I claim as new, and desire to secure by Letters Patent of the United States, is—

1. As a means of timing the opening and closing of the shutters of a camera and thus determining the length of the exposure, the air-chamber *E E'*, passage *d'*, sleeve *d''*, the taper plug-valve *F*, provided with the passages *f* and *g*, the flat surface *f'*, and the tapered peripheral groove *f''*, the flexible tube *G*, and the collapsible bulb *H*, all combined and arranged to operate substantially as and for the purposes described.

2. The combination of the expandable chamber *E E'*, the passage *d'*, and sleeve *d''*, the valve *F*, provided with the passages *f* and *g*, the cut-away or flat surface *f'*, and the tapered peripheral groove *f''*, the flexible tube *G*, the bulb *H*, the disk *p*, the rod *N*, the lever *D*, provided with the pendent arm *D'*, terminating in the double hook *b*, the shutter *C*, provided with the pins *c* and *c'*, and the shutter *C'*, provided with the pin *c''*, all arranged and adapted to operate substantially as described.

3. The combination of the expandable chamber *E E'*, provided with the passage *d'*, the valve *F*, provided with the passage *f g*, the cut-away *f'*, the tapered groove *f''*, and the arm *n'*, the hook-lever *M*, the spring *m*, the lever *L*, and the adjustable stop-pin *j*, all ar-

ranged and adapted to operate substantially as and for the purposes described.

4. The combination of the expandable chamber *E E'*, provided with the passage *d'*, the valve *F*, provided with the arm *n'*, the spring *m*, the hook-lever *M*, the lever *L*, secured upon said valve, the adjustable lever *J*, provided with the pointer *i*, and the stop-pin *j*, and the index-plate *I*, all arranged and adapted to operate substantially as described.

5. The combination of the valve *F*, provided with the arm *n'*, and lever *L* rigidly secured thereto, the spring *m*, the hook-lever *M*, the plate *I*, provided with the graduated scale *I'*, the lever *J*, provided with the index-pointer *i*, and the stop-pin *j*, the nut *k*, pivoted to said lever *J*, the adjusting-screw *K*, and the bearing *l* pivoted to the plate *I*, substantially as described.

6. The combination of an expandable air-chamber provided with an inlet and discharge passage, a device for forcing air into said chamber, and a valve provided with a tapered exhaust-passage and arranged to be automatically moved a greater or less distance to regulate the exhaust of air from said chamber, substantially as described.

7. In combination with a photographic camera, a pair of shutter-plates arranged one above the other and to be moved vertically in suitable guides and provided with supporting-pins, and a pivoted lever provided with a double hook to engage said pins and hold said shutters in an elevated position, and arranged to be vibrated in one direction to release the lower shutter-plate, and in the opposite direction to release the upper shutter-plate, substantially as described.

8. In combination with a lens-tube of a photographic camera, two shutters or lids arranged to be moved transversely across the end of said tube to open or close it, a device for locking and retaining said shutters in position with one shutter closing said tube, a device for releasing one of the shutters and causing it to uncover the lens-tube, and a timing mechanism arranged to be set in motion by said shutter-releasing device, and adapted to release the other shutter and cause it to cover the lens-tube at the end of any predetermined interval of exposure, substantially as described.

9. The combination of an expandable air-chamber provided with an inlet and discharge passage, and a valve provided with a tapered exhaust-passage and arranged and adapted to be moved a greater or less distance to regulate the exhaust of air from said chamber, substantially as described.

In testimony whereof I have signed my name to this specification, in the presence of two subscribing witnesses, on this 30th day of January, A. D. 1885.

Witnesses: CHARLES W. STIFF.
